MILLARD K. BROWN, OF EAGLE GROVE, IOWA

HOG GREASER

Application filed August 5, 1929. Serial No. 383,461.

My invention relates to a hog greaser in which I provide a central stationary support, which has mounted telescoping with and to oscillate thereon a perforated container for graphite grease. The top of the greaser is mounted on the stationary support so the bottom will have suitable clearance with the ground to provide for the oscillation of the greaser. This arrangement allows the graphite lubricant contained within the greaser to be expressed thru the screen in small quantities, during the period of oscillation, caused by the rubbing action of the hog against the screen of said greaser.

Further objects of my invention are to provide a greaser that has a universal oscillating movement with its stationary support and works automatically when oscillated, is simple and inexpensive to manufacture, and large enough to carry an adequate supply of grease which eliminates unnecessary attention. Since it is a well known fact that hogs like to rub, they will put the grease where they choose, thereby causing the destruction of lice and cleansing any scurfy condition which may exist among the hogs.

The full objects and advantages of my invention will appear in connection with the detailed description thereof, and the novel features of my invention idea will be particularly pointed out in the claims.

In the accompanying drawings which illustrate one form in which my invention may be embodied,—

Fig. 1 is a front elevational view. Fig. 2 is a vertical section on the line 2—2 of Fig. 5. Fig. 3 is a view similar to Fig. 2 showing the upper half but in a tilted position. Fig. 4 is a vertical section on the upper half of the line 4—4 of Fig. 5 in a tilted position. Fig. 5 is a top plan view. Fig. 6 is a sectional view of the lower half taken thru the fabric.

As shown in the drawings the greaser is made in two units so as to make a universal joint connection with its stationary support 2. The first unit of the greaser comprises a steel band 4 which is wide enough to allow it to be suspended on the stationary support and also will allow room enough for the

second unit which will be described later to be mounted thereon. This band also facilitates the universal swinging action which will be described later. Extending thru and near the top of the band 4 and the post 2 is a bolt 6 which allows the band 4 to oscillate thereon. This band is kept in central position on the post 2 by means of the compression springs 8, which are inserted on the bolt 6 between the outside of the post 2 and the interior of the band 4. Spaced in the lower part of the band 4 opposite and 90 degrees from the bolt 6 are bolts 10 which tie the band 4 and the second unit which will be described later together, so that the second unit is supported by a universal joint.

The second or interior unit consists of four flat steel legs 12, which are bolted by means of bolts 14 at their center and outer extremities to bands 16—18 and 20, and spaced equidistant around the periphery of said bands. This frame consisting of the four legs and three bands has wrapped around it a screen 22 which extends from the top of the band 16 to the bottom of the band 20. The ends of said screen 22 are inserted in a U shaped sheet metal strip 24 which clamps the ends of the screen together and holds it snug to the frame by means of the bolts 14, forming a tubular perforated casing.

To prevent the hog from cutting its hide and to protect the screen at the bottom, I have made a circular sheet steel band which is J shape in cross section. This shape of band allows me to slip the short leg 26 which is the same height as the width of the band 20 up from the bottom of the band 20 and outside of the screen 22. The long leg 28 which is twice the length of the leg 26 projects up from the bottom and around the interior of the ring 20, this allows a rigid construction at the bottom as all parts are held firmly together by the bolts 14. The purpose of the longer leg 28 is to allow it and the skirt of a cone shaped endless fabric or cloth to be riveted to an interior ring 32 by means of rivets 34. The fabric 30 has sewed in the cone end a coil spring 34 which fits snugly around the supporting post 2, thus forming a bottom member for the perforated

jacket heretofore described. To prevent the fabric from sagging at point 36 I have riveted eight plates 38 to the fabric spaced 90 degrees apart and placed as shown in Fig. 2 and Fig. 5 of the drawings. These plates 5 keep the fabric as shown in Fig. 2 and Fig. 6 in an upright cone shaped position, and reinforces it when it is in either position as shown in Fig. 3 and Fig. 4. This description 10 thus far shows that a perforated container has been formed in conjunction with the stationary support and as shown in the drawings the post forms the interior wall, the fabric the bottom, the screen or jacket the outside wall, thus leaving the top open and the bottom sealed. It will be obvious from 15 the drawings that the interior ring 32 and the coil spring which fits in the cone end of the fabric hold the graphite grease in the bottom of said container and prevents the grease from leaking past the supporting post 2, but forces it to find its way thru the screen 22 when the container or greaser is oscillated by the rubbing action of the hog against it. It is also clear in the drawings that the grease 20 is inserted into the container thru the opening in the top which heretofore has been referred to thus making a compartment of grease surrounding the stationary post and the interior of the jacket.

In order to accomplish the universal oscillation of movement heretofore referred to, you will notice the lower half swings on the bolt 40 when the hog pushes against the 25 greaser opposite the bolt 6, and in Fig. 4 the two units move as one when the hog pushes against the greaser opposite the bolts 10. In either one of these actions the lower part opposite the pivoting point of the greaser 30 swings in against the post 2 causing the grease that is in the lower part of the container to be compressed and forced out thru the screen upon the hog as he continues to rub against it. When the greaser retains its upright position as shown in Fig. 1 and Fig. 2 the 35 weight of the grease then finds its level in the container at the bottom making it ready from the action of the hog against it. This construction makes a self feeding proposition 40 and requires no attention except when it needs filling with the graphite grease, making it inexpensive to operate.

I claim:

1. A hog greaser comprising a container 45 adapted to receive a quantity of grease, means at elevation above at least a portion of a quantity of grease when in said container for supporting the container for universal lateral movement, and means adapted to cause grease to be discharged onto an external surface of said container when the container is moved laterally upon its support.

2. A hog greaser comprising a grease container, a support for an upper portion of said grease container adapted to allow the body

of the container suspended below the elevation of said support to be universally swung laterally, and means including the grease container body when swung laterally of said support to cause grease to be discharged onto an external surface of said grease container body. 70

3. A hog greaser comprising a grease container, and means for supporting an upper portion of said grease container for universal 75 swinging movement of a part of the container disposed below the elevation of said supporting means, said container being adapted when swung upon its support to discharge grease onto a part of its outer surface below said supporting means.

4. A hog greaser comprising a perforate container adapted to receive a quantity of grease, means at elevation above at least a portion of a quantity of grease when in said 85 container for supporting the container for lateral swinging movement in any direction, and means including the grease container adapted to cause grease to be discharged through perforations of said container onto its external surface when the container is 90 swung laterally upon its support.

5. A hog greaser comprising a stationary support, a container adapted to receive a quantity of grease, and means at elevation 95 above at least a portion of a quantity of grease when in said container for mounting the container for universal movement laterally of said support, said support and said container being adapted to cooperate with each other 100 when the container is swung laterally of the support to cause grease to be discharged onto an external surface of said container.

6. A hog greaser comprising a stationary support, a container surrounding said support adapted to receive a quantity of grease, and means at elevation above at least a portion of a quantity of grease when in said container for mounting the container for universal movement laterally of said support, 105 said support and said container being adapted to cooperate with each other when the container is swung laterally of the support to cause grease to be discharged onto an external surface of said container. 110

7. A hog greaser comprising a stationary support, a container surrounding said support adapted to receive a quantity of grease, and means at elevation above at least a portion of a quantity of grease when in said container for mounting the container for universal swinging movement upon said support, 120 said support and said container being adapted to cooperate with each other when the container is swung laterally of the support to cause grease to be discharged onto an external surface of said container. 125

8. A hog greaser comprising a stationary support, a perforate continuous wall surrounding said support in spaced relation 130

thereto, a skirt element within said wall and surrounding said support, the full perimeter of said skirt element being associated with said wall to provide therewith a grease container, and means at elevation above at least 5 a portion of a quantity of grease when in said container for mounting said wall for universal swinging movement upon said support said skirt element being adapted to cooperate with said walls to cause grease to be discharged onto an external surface of said wall when the wall is moved laterally of said support.
